UNITED STATES PATENT OFFICE

HENRY BERRY, OF HUNTINGTON, CONNECTICUT, ASSIGNOR TO THE DERBY SILVER COMPANY, OF SAME PLACE.

DESIGN FOR ICE-PITCHERS.

Specification forming part of Design No. **11,325**, dated August 12, 1879; application filed July 19, 1879.
[Term of patent 3½ years.]

To all whom it may concern:

Be it known that I, HENRY BERRY, of Huntington, in the county of Fairfield and State of Connecticut, have invented a new Design for Ice-Pitchers; and I do hereby declare the following, when taken in connection with the accompanying drawings and the letters of reference marked thereon, to be a full, clear, and exact description of the same, and which said drawings constitute part of this specification, and represent in—

Figure 1, side view; Fig. 2, horizontal section.

This invention relates to a design for the class of pitchers known as "ice-pitchers;" and consists in the shape and ornamentation, as shown in the accompanying illustration, and hereinafter described.

The body of the pitcher is oval in horizontal section, as seen in Fig. 2. Vertically it is straight, or of substantially equal diameter. Around the base is a molding, *a*, and directly above this base-molding is a double orna-

mented band, *b c*, a plain bead, *d*, between the two, and a similar bead, *e*, at the edge of the upper band. Around the top is a neck-molding, *f*, and below this an ornamented band, *h*. The decoration on the surface of the body, between the bands at the bottom and the band at the top, is in imitation of Japanese work; but this may be varied, as well as the handle, spout, and cover, without departing from the essential features of this design, which are the oval shape of the body, with the base-molding and bands at the bottom and neck-molding and band at the top.

I claim—

The design for ice-pitchers consisting of the oval-shaped body, with base-molding and bands *b c* at the bottom, and neck-molding and band *h* at the top, as described, and shown in accompanying illustration.

HENRY BERRY.
